POWDER COMPACT

August Mitchell, Middlebury, Conn., assignor to
The Risdon Manufacturing Company, Naugatuck,
Conn., a corporation of Connecticut

Application July 22, 1941, Serial No. 403,517

1 Claim. (Cl. 220—31)

The invention relates to powder-compact cases and its object is simplification and reduction of manufacturing cost, and particularly to make the powder-cake tray easily insertable and removable, by the simplest and least conspicuous means.

The invention is shown in the accompanying drawing wherein Fig. 1 is a vertical section through the hinge of the case, Fig. 2 a top plan, Fig. 3 a larger scale partial perspective, and Fig. 4 a diagram of the blank.

According to this invention, the box body 1 is made from a sheet metal blank in a punch press in the ordinary way and with a somewhat longer skirt portion than is required to constitute the circumferential wall of the finished box. This is represented by the dotted lines in Fig. 4.

Such long-cupped blank is then trimmed down to the general box-body dimension as indicated by the full lines in the same figure, but so as to leave a narrow finger 2 with a shallow notch 3 on each side of it.

When the box is reduced to finished form this integral finger 2 is curled over toward the inside of the box to form a hinge-knuckle 4 and its free end, reaching almost to the box bottom, is slightly bowed or otherwise shaped as a spring detent. This detent is for engaging the edge of the tray 5 on which the powder-cake is secured, to hold it down or in place after it has been placed in the box. The tray has the same shape as the box and fits it appropriately, so that it will ride over the hump of the detent or finger and

preferably snap under it, being thereafter held securely in position but capable of removal, when desired. By selecting the appropriate width for the finger, which is not too narrow to constitute a proper hinge-knuckle, the requisite resilience is obtained so that tray removal can be accomplished without use of excessive pressure.

Complementary hinge-knuckles 6 are formed on the cover 7, and the hinge is completed by 10 inserting the pintle 8, as will be understood, thus producing an extremely simple case of neat appearance and at very low cost. More than one knuckle can be provided on either the box or cover as desired, and if greater security is required for the compact tray the wall of the box body on the side opposite the hinge can be indented to form a small pimple marked 9 in a position to overlie the adjacent edge of the tray, and thus supplement friction in holding this edge of 15 the tray down.

A hinged case of the kind described comprising a stamped box body formed with an integral extension of its side wall, said extension being curled to form a hinge knuckle and its free end being extended within the box toward the bottom thereof and shaped as a spring detent, in combination with a tray adapted to fit within the box body to be engaged by and be retained in place by engagement with said detent, and a cover 25 for the box having complementary hinge-knuckle formation connected to said extension.

AUGUST MITCHELL.
